UNITED STATES PATENT OFFICE.

JOHN C. JUTHE, OF ALLSTON, MASSACHUSETTS.

DESIGN FOR A CHILD'S WHEEL TOY.

59,598.

Specification for Design.

Patented Nov. 8, 1921.

Application filed August 28, 1920. Serial No. 406,637. Term of patent 14 years.

To all whom it may concern:

Be it known that I, JOHN C. JUTHE, a citizen of the United States, residing at Allston, in the county of Suffolk and State of Massachusetts, have invented a new, original, and ornamental Design for a Child's Wheel Toy, of which the following is a specification, reference being had to the accompanying drawing, forming part thereof.

The drawing is a view in perspective looking down on the toy toward one corner of the rear end and showing my new design.

The forward portion 1 is much narrower than the rearward portion 2 of the seat and this narrower portion 1 extends centrally from the wider portion 2 and meets the wider portion with a curved shoulder

3 at each side. The steering handle 4 with its shank 5 and yoke 6 carrying the steering wheel 7 rotate on the vertical axis of the shank 5 and consequently the particular angular position of these parts with respect to the seat 1—2 forms no part of the design. The steering wheel 7 and the rear wheels 8 also rotate on their axes and consequently the particular angular position of the spokes shown forms no part of the design. The entire toy is symmetrical with respect to a vertical plane passing longitudinally through the center of the toy.

I claim:

The ornamental design for a child's wheel toy as shown and described.

JOHN C. JUTHE.
